(57) **CLAIM**

The ornamental design for a center console organizer box, as shown and described.

DESCRIPTION

FIG. 1 is a front, right, top perspective view of the center console organizer box, showing my new design;
FIG. 2 is a rear, left, bottom perspective view thereof;
FIG. 3 is a front, right, top perspective view of the center console organizer box in another angle;
FIG. 4 is a front elevational view thereof;
FIG. 5 is a rear elevational view thereof;
FIG. 6 is a left side view thereof;
FIG. 7 is a right side view thereof;
FIG. 8 is a top plan view thereof; and,
FIG. 9 is a bottom plan view thereof.
The dashed broken lines illustrate portions of the center console organizer box which form no part of the claimed design.
